UNITED STATES PATENT OFFICE.

JOHN H. STONE, OF CRANSTON, RHODE ISLAND.

METHOD OF FORMING RINGS.

Application filed November 23, 1918. Serial No. 263,901.

To all whom it may concern:

Be it known that I, JOHN H. STONE, a citizen of the United States, and resident of Edgewood, city of Cranston, in the 5 county of Providence and State of Rhode Island, have invented certain new and useful Improvements in Methods of Forming Rings, of which the following is a specification.

- 10 This invention relates to rings more particularly designed for personal wear, and has for its object to provide an improved construction of a so-called shell form of ring; also an improved method by which 15 such a ring is formed, the ring being made of two continuous bands of very thin stock, one of which is trough-shape on its inner surface and both of which are connected together, thereby forming a ring that is 20 strong and durable and that is made of precious metal and of the very minimum amount of stock.

With these and other objects in view, the invention consists of certain novel features 25 of construction, as will be more fully described, and particularly pointed out in the appended claim.

In the accompanying drawings:

Figure 1—is a side elevation showing a 30 ring of my improved construction.

Figure 2—is a perspective view of a piece of tubing from which the outer band of my improved ring is formed.

Figure 3—is a perspective view showing 35 a section cut from the tube from which my outer band is formed.

Figure 4—shows the outer band as bent or shaped into a concavo-convex form.

Figure 5—shows a plurality of these 40 outer concavo-convex bands mounted upon a tube and spaced apart at intervals along the same.

Figure 6—is a sectional view showing the edges of the outer band as secured to those of the inner band thus forming a shell ring 45 or one in which the ring band is hollow.

Figure 7—is a sectional view illustrating a set of bending dies in open position, employed for shaping the outer ring band into concavo-convex form, the die being shown 50 open with the band positioned therein ready to be shaped when the dies are forced together.

Figure 8—shows the dies as having been 55 closed and the band as bent into the desired form by the closing action of these dies.

Referring to the drawings, 10 designates a seamless tube of precious metal, which is drawn up from a disk into an elongated thimble of the required diameter. I next 60 cut by a saw, or otherwise, a narrow band member 11 from this tube and place this band between the two dies 12 and 13 which are hollowed out preferably as at 14 and 15 into the shape in which this band member is designed to be pressed, as illustrated in Figure 8. These dies are then forced together into the position illustrated in Figure 9, causing the band to take the shape of the cavity in the die. 70

I have shown the band thus formed to be of an oval shape as at 16 or concavo-convex in cross section, but the band may be shaped on its outer side into any desired form to produce rings of different styles. 75

The next operation is to draw up another tube or thimble 17 from a disk of precious metal. The diameter of this second tube being considerably smaller than that of the first tube. The inner diameter of the tube 80 from which the inner bands are constructed is of the size designed to determine the rated size of the ring and its outer diameter is just sufficient to fit inside of the inner edges of the outer concavo-convex band 16 previously formed. I then slip a plurality of these bands 16 onto this inner tube and arrange them in spaced relation set just far enough apart so that they may be readily soldered to the tube by the use of a gold 90 or silver solder, as at 19. When this is done I next saw off the tube on each side of each band, the edges are then burnished over and the ring is complete. This burnishing of the edges renders them very smooth and also 95 serves to completely cover the seam, rendering it quite invisible.

By this construction the two different bands 16 and 18 of the ring may be formed of precious metal of but a few thousandths of an inch in thickness or about the thickness 100 of an ordinary sheet of writing paper, and by shaping the outer band in an oval form and permanently securing it to the inner band the whole is made extremely stiff and strong. A ring so formed is very durable 105 and at the same time is extremely light in weight and while it may be properly sold for an all-gold ring yet it possesses the very minimum amount of precious metal. Then again both of the members of the ring are 110 continuous, unsoldered bands and the ring is formed without transverse seams.

By my improved construction of ring the stock from which it is constructed may be made so thin that a solid or all-gold ring may be sold at almost the same price as one formed partly of base metal of the old construction.

Having thus described one illustrative embodiment of my invention and the best mode known to me for carrying out my method, 10 I desire it to be understood that although specific terms are employed, they are used in a generic and descriptive sense and not for the purpose of limitation, the scope of the invention being defined and limited only by 15 the terms of the appended claim.

I claim:

The method of forming a hollow ring band which consists in cutting a band from a tube applying an edgeways pressure upon this band by a forming die bending it into concave shape in cross section, securing a plurality of these bands at spaced apart intervals upon a tube then severing the tube at the edges of the outer band and finishing the edges. 20

25 In testimony whereof I affix my signature in presence of one witness.

JOHN H. STONE.

Witness:

HOWARD E. BARLOW.
